UNITED STATES PATENT OFFICE

HARDY W. CAMPBELL, OF ABERDEEN, SOUTH DAKOTA, ASSIGNOR TO
THERON H. GREEN, OF MINNEAPOLIS, MINNESOTA.

HEATER.

SPECIFICATION forming part of Letters Patent No. 502,701, dated August 8, 1893.

Application filed September 6, 1892. Serial No. 445,164. (No model.)

To all whom it may concern:

Be it known that I, HARDY W. CAMPBELL, a citizen of the United States, residing at Aberdeen, in the county of Brown and State 5 of South Dakota, have invented certain new and useful Improvements in Heaters; and I do hereby declare the following to be a full, clear, and exact description of the invention, such as will enable others skilled in the art 10 to which it appertains to make and use the same, reference being had to the accompanying drawings, and to the letters of reference marked thereon, which form a part of this specification.

15 The herein described invention relates to certain improvements in devices by which much of the heat which ordinarily passes into the chimney, is utilized to heat the same or an adjoining apartment to that in which the 20 stove is located, and to further provide for a circulation of the air in the apartment to the end that a uniform heating of the same throughout may be accomplished.

The invention consists in certain novel features in the arrangement and construction of parts, all as hereinafter set forth and pointed out in the annexed claims.

In the accompanying drawings, in which my invention is fully illustrated, Figure 1 is 25 a view in side elevation of the device arranged to heat a room adjoining that in which the stove is stationed, the smoke-pipe of the stove extending through the partition wall. Fig. 2 is a perspective view of the heating-drum or 30 radiator, a portion thereof being shown as broken away to disclose the inner air-circulating pipe and the deflecting-wing provided thereon. Fig. 3 is a perspective view of the 35 adjustable section of the drum having the smoke-pipe connected therewith. Fig. 4 is a top view of the same, and Fig. 5 is a perspective view of one of the devices for making the 40 jointed sections of the drum adjustable.

45 Referring to the drawings by letter A indicates the drum or radiator which rests on the floor of the apartment and extends nearly to the ceiling and may be located in the same room with the stove B, or within an adjoining room, the latter arrangement being preferable as by this means one stove may be 50 made to heat two rooms.

The drum A communicates with the stove-pipe C at or near the base of the drum and with the chimney D by means of pipe E, which enters the drum near the top of the same. 55 Within the drum A is located a pipe F, extending the entire length of the drum and communicating with the air of the room through the top of said drum at F', which, with the exception of this opening for pipe F, 60 is completely closed at the top. The function of pipe F is simply that of an air-circulating pipe which as the air within the same is heated, draws the air from the bottom of the room through the air-inlets G at the base of the 65 drum. By the circulation of air thus effected within a short time all the air of the room will have passed through the circulating-pipe F and be heated, while a great deal of heating is accomplished by radiation from the exterior 70 of the drum or radiator A.

The space between the inner or air-circulating pipe F and the drum A, is obstructed at certain points by means of circular partitions or wings H, which extend half way 75 around the inner pipe and project flush with the inner face of the drum, thus effectually partitioning the space and causing the smoke and heated air to be directed to the open side to get above the partitions as they are met. 80 These are arranged alternately on one side and then the other of the pipe and in their combined action cause the smoke to travel from one side to the other in ascending the drum to pipe E, thus retaining the heat of the 85 same some little time within the drum by reason of its circuitous route and giving a greater amount of heat than would otherwise be obtained. A vertical partition I is also provided on each side of pipe F and preferably 90 joined to the wing H located just above the smoke pipe C, which causes the smoke to descend to near the base of the drum and to heat the same through its full length.

The drum A as well as the inner circulating-pipe F is required (by reason of the variation met with in the size of rooms and locations of chimney-openings) to be made adjustable and thereby make it possible to adapt the radiator to various places. The top section 95 J and intermediate section K of the drum A and section L of the air-circulating pipe, are 100

constructed as shown in Figs. 2, 3, and 4, the sheet metal forming the pipe or drum being lapped and provided on each lap with a casting *M*, shown in Fig. 5, which casting is firmly secured one on each side and connected one with the other by means of bolts *n* which permit the laps to be drawn together and the size of the pipe or drum section adjusted as desired. The top of each section referred to is firmly riveted as shown at *O*.

Having thus fully described my invention, what I claim as new, and desire to secure by Letters Patent of the United States, is as follows:

- 15 1. The means for heating adjoining rooms which consists in a stove arranged in one of said rooms in connection with the smoke pipe of said stove, leading through the wall separating the rooms a long vertical drum arranged in the second room, and extending from the floor to a point near the ceiling of said room, the smoke pipe of said stove leading into said drum a flue or chimney a con-

nection with the upper end of said drum, a vertical open duct *F*, arranged within said drum and adapted to take the air from the floor line and a series of segmental, inclined wings arranged between said duct *F*, and the wall of the drum, substantially as described.

2. The combination in a heating device, of the long drum and air duct *F*, arranged therein, a smoke pipe leading into opposite ends of said drum, the inclined wings *H* secured upon said duct and extending between the same and the inner walls of said drums, the lower wing *H* provided with downwardly projecting partitions *I*, said drum formed of single sheets of metal, having their edges brought together and held by the angle castings *M* and short bolts *n*, substantially as described.

In testimony whereof I affix my signature in presence of two witnesses.

HARDY W. CAMPBELL.
